UNITED STATES PATENT OFFICE

171,949

TROUSERS HANGER OR SIMILAR ARTICLE

Charles Owen Merry, Decatur, Ill.

Application November 2, 1953, Serial No. 27,417

Term of patent 7 years

(Cl. D80—8)

To all whom it may concern:

Be it known that I, Charles Owen Merry, a citizen of the United States, residing at Decatur, in the county of Macon and State of Illinois, have invented a new, original, and ornamental Design for a Trouser Hanger or Similar Article, of which the following is a specification, reference being had to the accompanying drawing, forming a part thereof.

Figure 4 is an enlarged elevational view of the backplate of my new design, showing in clearer detail the design thereon.

The back of the plate, not shown, is plain or conventional.

I claim:

The ornamental design for a trousers hanger or similar article, as shown and described.
